UNITED STATES PATENT OFFICE.

VICTOR ANTONI, OF CHICAGO, ILLINOIS.

COLLAR.

1,147,691.

Specification of Letters Patent. Patented July 20, 1915.

Application filed April 24, 1914. Serial No. 834,169.

To all whom it may concern:

Be it known that I, VICTOR ANTONI, a citizen of the United States, residing at Chicago, in the county of Cook and State 5 of Illinois, have invented certain new and useful Improvements in Collars, of which the following is a specification.

This invention relates to improvements in collars and has for its object to provide a 10 collar so constructed that a tie may be attached thereto after the collar has been fastened to the shirt.

Another object of the invention is to provide a reversible collar so formed as to reduce the friction between a tie or cravat 15 and the collar.

With the above and other objects in view I have invented the collar illustrated in the accompanying drawings in which:—

20 Figuré 1 is a perspective view of my improved collar; Fig. 2 is a front plan view of the collar as it appears fastened to the shirt.

Like reference characters designate like 25 or corresponding parts throughout the different views in which 1 indicates my improved collar which is of that class of collars known as a turn over collar and connected to the upper edge of the main portion 2 there- 30 of is a portion 3. The turn of the portion 3 may be of the same length as the collar or slightly longer as indicated in Fig. 2 of the drawings. Depending from the ends 4 and 5 of said turn-over portion are tabs 35 6 and 7 which are provided with ordinary button holes 8 and 9. The main portion of the turn over part 3 of the collar is relatively very much narrower than the body portion 2, of the collar, whereas said tabs 40 6 and 7, may be of any desired depth. Also projecting from the portion 3, at the rear portion is a tab 10, having a button hole 11, adapted to engage the back collar button of the shirt. In use the rear tab 10, of this 45 collar is fastened to the shirt after which a neck-tie is shoved between said tab and the body portion of the collar, then the tabs 6 and 7, are fastened to the front collar button and the opposing ends of the tie are 50 brought together and tied, and then slipped

between the tabs 6 and 7, and the relative portions of the body part of the collar. The tie may then be adjusted with greatest ease and comfort and practically little, if any, friction, is brought thereon by said tabs and 55 the collar. The construction of this collar is such that it may be readily reversed in order that both sides of the body portion of the collar may be exposed in wear. This collar, besides, permitting easy adjustment 60 of a tie is also exceptionally comfortable as it does not bind the neck as tightly as the ordinary collar, and is much cooler than the ordinary turn over collar. Another way of using the collar is to fasten the rear tab 65 10 to the shirt and then fasten the tabs 6 and 7 after which the neck tie is placed upon the projecting end of the tab 10 a little below the edge of the collar with the ends of the tie hanging over the shoulder of the 70 wearer then take hold of the ends of the tie and sawing the same backward and forward gradually drawing it into place under the collar 2. The rear collar button will prevent the tie from rising high enough 75 under the collar to slip off of the shirt band, the tab 10 extending sufficiently below the bottom edge of the collar to permit the tie to overlay the tab 10 after said tab has been buttoned to a shirt band whereby the tie 80 may readily be guided into place between the tab 10 and the collar 2 and below the button hole 11.

Having now described my invention that which I claim to be new and desire to procure by Letters Patent is:—

1. A collar having a turn over outer portion, a rear tab projecting substantially from the upper edge of said collar to below the lower edge thereof and having a button hole 90 therein above said lower edge.
2. The described collar having an outer turn-over portion and a relatively very narrow inner band having tabs on its ends and a centrally disposed tab, said tabs projecting below the lower edge of said outer portion, said tabs having button holes above said lower edge, the button hole on said centrally disposed tab being so located that a button projecting therethrough will pre- 100

vent a necktie from riding above the shirt band to which said collar is attached, said centrally disposed tab adapted to act as a guiding means whereby said tie may be 5 guided into position between said tab and the outer portion.

Copies of this patent may be obtained for five cents each, by addressing the "Commissioner of Patents, Washington, D. C."

In testimony whereof I affix my signature in presence of two witnesses.

VICTOR ANTONI.
